UNITED STATES PATENT OFFICE.

CHARLES WILLIAM ALEXANDER TAYLOR, OF DUNSTON-ON-TYNE, ENGLAND.

RUDDER-BRAKE.

1,401,290.

Specification of Letters Patent. Patented Dec. 27, 1921.

Application filed February 18, 1920. Serial No. 359,632.

(GRANTED UNDER THE PROVISIONS OF THE ACT OF MARCH 3, 1921, 41 STAT. L. 1313.)

To all whom it may concern:

Be it known that I, CHARLES WILLIAM ALEXANDER TAYLOR, a subject of the King of the United Kingdom of Great Britain and 5 Ireland, and residing at Dunston-on-Tyne, England, have invented a certain new and useful Improvement in Rudder-Brakes, (for which I have filed application in England, Jan. 19, 1915, Patent Number 854,) of which 10 the following is a specification.

The subject of this invention is a rudder brake designed to damp the vibratory movements of ships' rudders.

The invention is illustrated in the accompanying drawing in which Figure 1 is an elevation, Fig. 2 a plan and Fig. 3 a detail sectional view drawn to a larger scale.

The rudder brake shown comprises an axle 1 rigidly mounted on the rudder quadrant 2 and engaging the tiller 3.

Sleeving the stub shaft 1 and revoluble thereon is a drum 4 or sheave wrapped by a rope-way 5 the terminal ends of which are secured to brackets 6, 7 located respectively 25 in the port side and the starboard side of the deck 8. It will be seen that as the quadrant swings from side to side the drum 4 or sheave will revolve about the stub shaft 1.

To resist the rotary movements of the 30 drum or sheave, there is fitted in the stub shaft 1 braking means comprising a ring 9 of friction material, such as wood embedded in the body of the stub shaft 1 and engaging the under surface of the drum or sheave 4, a plate 10 abutting against the upper surface of the drum or sheave 4, a bolt 11, a nut-forming hand wheel 12 for regulating the pressure applied to the friction surfaces and a spring 13 interposed between the head 14 35 of the bolt 11 and the under surface of the stub shaft crown 15 for applying the pressure to the friction surfaces. To prevent rotation of the plate 10 with the drum 4 or sheave, dowel pins 16 are provided, and 40 dowel pins 17 are provided to prevent rotation of the bolt 9.

It will be understood that the pressure on the friction surfaces will be regulated by manipulation of the hand wheel 12 to suit 45 weather conditions at sea.

Formed on the wearing surfaces of the plate 10 and on the cylindrical surface of the stub shaft 1 are lubricant pockets 18.

A stretching screw 19 is provided for maintaining the rope-way taut. 55

I claim:

1. The combination with a rudder quadrant of a drum rotatably mounted thereon and bodily movable therewith, a thwartship rope-way wrapping, and adapted to be 60 traveled by said drum, and braking means for resisting the rotary movements of said drum and thereby damping the movements of said rudder quadrant.

2. A rudder brake comprising, in combination, a rudder quadrant, a stub shaft rigidly mounted thereon, a drum revolvable on said stub shaft, a thwartship rope-way wrapping said drum, friction means engaging said drum, resilient means for applying 70 pressure to said friction means and pressure regulating means.

3. The combination with a rudder quadrant of a sheave mounted to revolve on said quadrant, means for retarding its revolution 75 by friction, a rope passing around said sheave so arranged that the working of the quadrant from side to side will cause the sheave to revolve and the rope to wind on one side and wind off on the other side, and stretching means attached to the ship's deck for setting up said rope taut between the ends. 80

4. The combination with a pivoted rudder quadrant, of a drum rotatably mounted on said quadrant eccentrically of the pivot of 85 said quadrant, a rope wrapping said drum, anchorages for the ends of said rope, and means for braking the rotation of said drum.

5. The combination with a rudder quadrant mounted for angular movement, of a 90 drum rotatable in the movement of said quadrant, a rope wrapping said drum, anchorages for the ends of said rope and means for braking the rotation of said drum.

6. A rudder brake comprising, in combination, a rudder quadrant, a stub shaft rigidly secured to said quadrant, a drum rotatable on said stub shaft, a thwartship rope-way wrapping said drum, a friction ring embedded in the body of said stub shaft and engaging 100 the under surface of said drum, a plate engaging the upper side of said drum, a nut-forming hand wheel engaging said plate, a bolt provided with a head and in screw-threaded relation with said wheel and a 105 spring acting on the head of said bolt to.

force said plate into engagement with said drum and thereby to press the under surface of said drum into frictional engagement with said ring so as to retard rotation of said drum.

7. A rudder brake comprising, in combination, a rudder quadrant, a stub shaft rigidly secured to said quadrant and provided with lubricant pockets on its cylindrical surface, 10 a drum rotatable on said stub shaft, a thwartship rope-way wrapping said drum, a friction ring embedded in the body of said stub shaft and engaging the under surface of said drum, a plate engaging the upper side of said drum and formed with lubricant pockets on its contact face, a nut-forming hand wheel engaging said plate, a bolt provided with a head and in screw-threaded relation with said wheel, and a spring acting 15 on said bolt head to force said plate into engagement with said drum and thereby to press the under surface of said drum into frictional engagement with said ring so as to retard rotation of said drum.
- 20 8. A rudder brake comprising, in combination, a rudder quadrant, a stub shaft

rigidly secured to said quadrant, a drum rotatable on said stub shaft, a thwartship rope-way wrapping said drum, a friction ring embedded in the body of said stub shaft 30 and engaging the under surface of said drum, a plate engaging the upper side of said drum, dowel pins connecting said plate with said stub shaft to prevent rotation of said plate, a nut-forming hand wheel engaging said plate, a bolt provided with a head and in screw-threaded relation with said wheel, dowel pins connecting said head with said stub shaft to prevent rotation of said bolt, and a spring acting on said bolt 35 40 head to force said plate into engagement with said drum and thereby to press the under surface of said drum into frictional engagement with said ring so as to retard rotation of said drum.

In testimony whereof I have signed my name to this specification in the presence of two subscribing witnesses.

CHARLES WILLIAM ALEXANDER TAYLOR.
